[57] CLAIM

The ornamental design for a grapple deflector for logging trailer, as shown and described.

DESCRIPTION

FIG. 1 is a front perspective view of a grapple deflector for logging trailer showing my new design;

FIG. 2 is a rear perspective view;

FIG. 3 is a top plan view thereof;

FIG. 4 is a front side elevational view, the rear side being a mirror image thereof;

FIG. 5 is a side elevational view as seen from the right side of FIG. 4;

FIG. 6 is a side elevational view as seen from the left side of FIG. 4;

FIG. 7 is a bottom view thereof; and,

FIG. 8 is a reduced scale perspective view of the present invention mounted on a trailer which is shown in broken lines to illustrate environmental structure. The broken line showing of the trailer forms no part of the claimed design.
